UNITED STATES PATENT OFFICE

ALFRED W. BRUCE, OF NEW YORK, N. Y.

LOCOMOTIVE CYLINDER AND SUPPORTING STRUCTURE THEREFOR

Application filed May 7, 1929. Serial No. 361,038.

This invention relates, generally, to cylinders and supporting structures therefor, and contemplates a three piece construction comprising the cylinder saddle, and two side cylinders.

An object of the invention is to provide a simpler and stronger connection between the locomotive frames and the cylinder assembly. Another object is to combine the cylinder saddle and adjacent cross ties in a one piece or integral construction. Another object of the invention is to provide improved means for proper attachment of the engine truck center pin or center pin guide. A further object is to provide means for obviating leaks in the exhaust steam connections. Another object is to provide for making the cylinder saddle of cast steel and the cylinders of cast iron. A further object is to provide a disposition of the bolts and nuts for securing the saddle to the frames and the cylinders to the saddle so that they will be readily accessible to the operator. Other objects of the invention will hereinafter appear.

The conventional type of cylinder construction embodying two parts joined at the center line of the locomotive, does not provide as much bolting area for attachment to the main frames as is desirable for many of the large size locomotives now being built. Furthermore the attachment of the various cross ties and truck center pin or center pin guide presents a matter of considerable difficulty. In the present invention the cylinder saddle is formed separate from the cylinders and is provided with front and rear extensions to provide additional bolting area and to take the place of the fore and aft cross ties formerly used.

The improvement claimed is hereinafter fully set forth.

In the accompanying drawings: Figure 1 is a transverse vertical view, partly in section, of a structure embodying the invention, part on the line $a-a$, and part on the line $b-b$ Fig. 2; Fig. 2, a longitudinal vertical view, partly in section on the line $d-d$ Fig. 1; and, Fig. 3, a longitudinal horizontal

view of the same, partly in section, on the line $c-c$ Fig. 1.

In the practice of the invention referring descriptively to the specific embodiment thereof which is herein exemplified the construction comprises a cylinder saddle member, 10, formed with a front extension 10a, and a rear extension 10b. A cylinder casting 11 comprises a cylinder and steam chest, is bolted to each side of the cylinder saddle.

The cylinder saddle member comprises the saddle proper 10c, which is a hollow box like casting having a front wall 10d, a rear wall 10e, two vertical side walls, 10f, a top wall, 10g, and a bottom wall, 10h.

Each side wall, 10f, is formed with an oblong recess 10j, adapted to receive a main frame, 12, and is provided at each end with a vertical lateral flange 10k. The vertical wall of the recess is provided with holes for the bolts 10m, which secure the saddle to the main frame. The portions of the side wall, 10f, above and below the recess are provided with holes for bolts 10n which secure the cylinder castings to the saddle. The main frames are provided with suitable countersinks 12a, in the area abutting the cylinder castings, to receive the heads of the bolts, 10m.

Each cylinder casting 11 comprises an inner vertical wall 11a adapted to fit tightly at its margins against one of the side walls of the saddle. The vertical margins 11b, extend beyond each end of the cylinder to provide vertical flanges, for attachment of the bolts 10n by which the cylinder casting is fastened to the saddle. The upper and the lower horizontal margin of the wall, 11a, is each provided with suitable holes for the bolts 10n by which the cylinder casting is additionally fastened to the saddle.

The front extension 10a, of the saddle member comprises two vertical side walls 10p adapted to fit against the main frames, and to receive the bolts 10q which pass through the main frame. The extension 10a also comprises a horizontal transverse reinforcing web 10r, and a vertical transverse wall 10s adapted to receive the bolts 10t by which the bumper casting 13 is fastened.

It is to be noted that the front extension, in addition to providing a greatly extended area for bolting the saddle to the main frames, also takes the place of the cross tie 5 formerly employed for bracing the structure.

The rear extension, 10b, comprises a horizontal reinforcing web, 10u, and two vertical side walls, 10v, adapted to fit against the main frame, and to receive the bolts 10w, 10 which pass through the main frame. It is to be noted that the rear extension in addition to providing a greatly extended area for bolting the saddle to the main frames, 15 also takes the place of the cross tie formerly employed for bracing the structure. The front and the rear walls of the saddle 10 are each provided with a manhole 10x to permit ready access to the attaching bolts.

The exhaust connection for each steam 20 chest, comprises a cast elbow 14, which is housed inside the saddle and is fitted with a ball joint ring on the lower end that projects through an opening in a side wall of the saddle and fits into the oppositely formed 25 end of a conduit 15, leading from the steam chest 16. The lower end of the elbow is provided with a bolting flange by which the joint ring of the conduits 14 and 15 is drawn into steam tight fit, the flange being 30 bolted to the cylinder casting 11 by bolts (not shown). The upper end of the elbow 14 is provided with a flange for bolting it by bolts (not shown) to the exhaust passage 19.

35 The engine truck center pin 17, in the case of four wheel trucks, is recessed in the bottom wall, 10h, of the saddle, providing an extremely simple and rigid construction. In the case of two wheel trucks, the center 40 pin guide may be formed integrally with the front extension of the cylinder saddle.

In assembling the improved construction the saddle member 10 is first fastened to the main frames by the bolts 10m, 10g, and 45 10w, and the cylinders are next attached, all of the bolts 10n being driven from the inside so that the nuts are open for inspection at all times. The cylinders are held in place not only by the bolts, 10n but by 50 a suitable key 18, applied from the outside, and having a very slight taper and only enough draw to properly position and secure the cylinders.

An important advantage of the invention 55 is the greatly increased bolting area provided for securing the saddle to the main frames. Another advantage of the invention is the provision of a saddle member combining in an integral structure the saddle proper and means performing with increased efficiency the reinforcing functions formerly performed by separate cross ties. A further advantage of the invention is the provision of a leak proof exhaust steam 60 connection through the saddle which is eco-

nomical to manufacture and easy to install and maintain. A further advantage of the invention is that the saddle may be made of cast steel and the cylinder castings of cast iron so that in the event of cylinder failure 70 repairs can be economically and expeditiously effected.

While one of the preferred embodiments of the invention has been described it is to be understood that various changes in form, 75 proportions, material, and assembly may be resorted to without departing from the spirit and scope of the invention set forth in the appended claims.

The invention claimed and desired to be 80 secured by Letters Patent, is:

1. A one piece cast structure adapted to be interposed between and secured to, the main frame side members of a locomotive, comprising a cylinder saddle having cylinder engaging side walls each formed with a recess for the reception of a main frame side member; and a rear extension embodying a longitudinal flange at each side adapted to be bolted to one of the main frame side 90 members, and a transverse member connecting and reinforcing the flanges, said extension being of a length and strength to take the place of a cross tie.

2. A one piece cast structure adapted to be interposed between and secured to, the main frame side members of a locomotive, comprising a cylinder saddle having cylinder engaging side walls; a rear extension embodying a longitudinal flange at each side 100 adapted to be bolted to one of the main frame side members, and a transverse member connecting and reinforcing the flanges; and a front extension embodying a longitudinal flange at each side, adapted to be 105 bolted to one of the main frame side members, and a transverse member connecting and reinforcing the flanges.

3. A one piece cast structure adapted to be interposed between and secured to, the main frame side members of a locomotive, comprising a cylinder saddle having cylinder engaging side walls; a center pin disposed beneath the saddle; and a front and a rear extension, each extension embodying 110 a longitudinal flange at each side each adapted to be bolted to one of the main frame side members, and a transverse member connecting and reinforcing the flanges.

4. A one piece cylinder saddle casting, 115 comprising side walls each formed intermediate its top and bottom with a longitudinal recess adapted to receive a locomotive main frame side member, said recess having holes at its side for bolts for attaching the casting to a main frame side member, each of the portions of each side wall, above and below the recess, having a longitudinal row of holes for bolts for attaching a cylinder casting to the saddle, and two laterally pro- 120 125 130

jecting vertical flanges adapted to cooperate with the bolts to hold the cylinder casting in place.

5. A one piece cast structure adapted to be interposed between and attached to the main frame side members of a locomotive, comprising a cylinder saddle, having side walls each formed intermediate its top and bottom with a longitudinal recess adapted 10 to receive a locomotive main frame side member, both portions of each side wall above and below the recess being provided with holes for bolting a cylinder casting to the saddle; and extensions to the front and 15 the rear of the saddle each extension embodying a longitudinal flange at each side adapted to be bolted to one of the main frame side members, and a transverse member connecting and reinforcing the flanges.

20 6. A locomotive cylinder saddle adapted to be interposed between and attached to the locomotive main frame side members, and comprising a one piece casting embodying a top and side walls each formed with an opening 25 each of the side walls being adapted for the attachment of a cylinder casting; and an exhaust steam pipe elbow detachably fitted within the saddle through the top wall opening and a side wall opening, the ends 30 of said elbow having bolting flanges adapting it to be bolted at its lower end to a working cylinder exhaust passage and at its upper end to the smokebox exhaust passage, whereby a steam tight joint may be 35 effected.

7. A one piece casting adapted to be interposed between and secured to, the main frame side members of a locomotive, comprising a cylinder saddle having oppositely 40 disposed cylinder engaging side walls provided each with an exhaust pipe opening; a support for the locomotive boiler between and in line with said side walls having an exhaust pipe opening; and a front extension 45 embodying a longitudinal flange at each side adapted to be bolted to one of the main frame side members, and a transverse member connecting and reinforcing the flanges, said extension being of a length and strength 50 to take the place of a cross tie.

8. A one piece casting adapted to be interposed between and secured to, the main frame side members of a locomotive, comprising a cylinder saddle having cylinder 55 engaging side walls; and a front extension embodying a longitudinal flange at each side adapted to be bolted to one of the main frame side members, and a transverse member connecting and reinforcing the flanges, 60 having a flange at its front end for bolting to a bumper casting.

9. In a locomotive the combination of main frame side members; a one piece cast structure having a front extension, interposed between and secured to, said members

throughout its entire length, said structure having side walls; and detachable working cylinders supported on said side walls.

10. In a locomotive the combination of main frame side members; a one piece cast structure having a front extension, interposed between and secured to said members, said members being extended forwardly of said structure, said structure having side walls; detachable working cylinders supported on said side walls; and a bumper casting adjacent the forward end of said structure between the forward ends of said members.

11. In a locomotive the combination of a steam boiler; main frame side members; a one piece cast structure having front and rear extensions, interposed between and secured to, said members throughout its entire length, said structure having side walls; detachable working cylinders supported on said side walls; and a support on said structure for the boiler.

12. In a locomotive, the combination of main frame side members; a one-piece cast structure interposed between and secured to the side members, comprising a cylinder saddle having cylinder engaging side walls, a rear extension embodying a longitudinal flange at each side bolted to one of the side members, and a transverse member connecting and reinforcing the flanges, said extension being of a length and strength to take the place of a cross tie; and detachable working cylinders having walls supported on and secured to said side walls, the said walls of the cylinders and saddle being spaced apart over a portion of their opposed surfaces providing housings for the side members.
